ROTOR GOVERNOR

Rudolph F. Onsrud, Chicago, Ill., assignor to
 Onsrud Machine Works, Inc., Chicago, Ill., a
 corporation of Illinois

Application August 25, 1945, Serial No. 612,572

6 Claims. (Cl. 253—52)

1

In fluid-driven motors, principally of turbine type and especially where high speeds are concerned, there is no known means of automatically adjusting the fluid input to fluctuating loads. The use of fly weights, springs, etc., on a rotating member for governing the speed thereof is impractical for high speeds because of the connections that must be made with a stationary part. Such connection is subject to exceptional frictional heat resulting in a rapid wearing away of the materials and thereby spoiling the adjustment. Because of the high speed of a turbine rotor—say for example, five miles per minute—any rotating flexible device for governing speeds becomes rigid and inflexible in the speed range in which the automatic adjustment is necessary.

The device of the present disclosure makes use of the fact that a high speed rotating wheel is expanded radially to some degree by centrifugal force proportionately to its speed of rotation and utilizes this expansion to control a throttle valve in the power medium supply for governing such speed.

The main objects, therefore, of the present invention are to provide an improved form of governor for high speed rotation; to provide improved means sensitive to the centrifugal expansion of the rotating part for controlling a fluid-driven mechanism; to provide an improved form of centrifugally actuated governor for controlling the fluid delivery nozzle of a turbine; and to provide improved throttle-valve actuating mechanism for devices of this kind.

A further object is to provide an improved mechanism for controlling the power supply to a fluid-pressure driven machine, by means which senses the location of a relatively moving surface without having physical contact with such surface.

A specific embodiment of the present invention is illustrated in the accompanying drawings in which:

Figure 1 is a plan view of a speed governing device made in accordance with this invention for controlling the speed of a vertical spindle driven by a horizontally disposed turbine wheel using air under pressure as the source of power.

Fig. 2 is a vertical section of the same taken generally on the line 2—2 of Fig. 1 but deviating slightly from the plane of said line in order to include in the view certain parts lying at one side of that plane.

Fig. 3 is a vertical section taken at right-angles to the plane of section of Fig. 2 on the irregular line 3—3 of Fig. 1.

2

Fig. 4 is a sectional detail taken on the line 4—4 of Fig. 2.

In the form shown in the drawings, the turbine wheel or rotor 1 is fast on a spindle 2 carried by ball bearings 3 and has formed in its rim portion 4 the usual annular series of bucket blades 5. The periphery 6 is of smooth cylindrical form and the rotor is made of suitable material, such as an aluminum alloy whereby, when driven at the high speeds of such turbine rotors, its periphery would have a perceptible amount of expansion which varies with the speed of rotation of the rotor.

The housing 7 has a fluid discharge nozzle 8 positioned so as to direct a jet of fluid against the buckets 5 for driving the rotor. The housing also has an appropriate exhaust outlet 9 at the opposite side of the buckets 5.

Fluid under pressure, in this case air, is supplied to the nozzle 8 by a pipe 10 which is connected to the inlet duct 10 and has the usual stop valve (not shown) for admitting and cutting off the supply of fluid to the nozzle 8.

The governing device comprises a housing 11 formed integrally with the rotor housing and having a cylindrical bore or chamber 12 in axial alignment with the nozzle 8. The outlet passage 13 leading from the chamber 12 to the nozzle 8 is tapered and has mounted therein a needle valve 14 which is controlled and guided in its movements by an actuator 15 which is slidably mounted in the chamber 12 to control the discharge at said nozzle.

In the form shown, the actuator is in the nature of a freely movable piston and comprises a stem for the needle valve 14 of less diameter than the diameter of the chamber 12 so as to provide a passage 16 for the free flow of fluid from the inlet passage 10 to the outlet passage 13. The end of the actuator 15 adjacent the outlet 13 is tapered and provided with spider arms 17 between which there are openings 18 for the passage of fluid.

The opposite end of the actuator 15 has a piston head 19 and there is a by-pass duct 20 formed in or at one side of the periphery of this piston to permit a small amount of fluid to pass into the part of the chamber 12 which is beyond the end of the piston 19. The actuator is so arranged that it is highly sensitive to the difference in pressures between the two sides of the piston 19 and is of such length that the passage 16 will at all times be in free communication with the inlet 10, regardless of the position of the piston 19. The face of the piston which carries

the needle valve 14 is of less effective area than its other face so that the piston will close the valve when both faces are exposed to the same pressure.

A bleeder pipe 21, of small diameter but of greater area than the by-pass in the piston, is connected into the chamber 12 adjacent the cylinder head 22 and extends to a point where the rim of the outlet 23 at its end is directly opposed to the periphery 6 of the turbine wheel. A tapered pin 24 threaded at 25 into the housing and having a knurled head 26 and lock nut 27 provides for micrometrical adjustment of the space between the outlet end 23 of the bleeder pipe 21 and the periphery 6 of the turbine rotor 1. To this same end, the pipe 21 should be of resilient material so that it normally bears outward against the pin 24.

The operation of the device shown is as follows:

When the fluid inlet valve (not shown) is opened and the fluid supply is admitted to the inlet 10, the piston 19 will be forced backward by the pressure of the fluid and the nozzle 8 will be open for maximum flow of air to the turbine.

So long as the gap between the outlet 23 of the tube 21 and the periphery of the rotor 6 is sufficiently large to allow the escape of air at this point to the full capacity of the bleeder passage 20 in the piston 19, the piston will remain at the backward limit of its stroke and as the speed of the turbine wheel increases centrifugal expansion of its periphery 6 tends to close the gap at the outlet 23.

When this gap is such that its capacity is less than that of the by-pass 20, then pressure will build up behind the piston 19 in the chamber 12 and the piston will be forced forward causing the valve 14 to partly or wholly cut off the supply of air at the nozzle 8. This movement of the valve can be so balanced that a small fraction of .001 inch of variation in the gap will cause the plunger to move forward or back.

The micrometrical adjusting screw 24 regulates this gap and thus determines the maximum and minimum consumption of fluid relative to speed range.

This governor also acts as a safety device to partly or totally shut off air in the event of overrunning. Overexpansion of the rotor would entirely close the by-pass, force the needle valve forward and choke the nozzle orifice to the limit provided for.

In the form shown, variation in the gap at the outlet 23 is produced by radial expansion of the rim of the turbine rotor, but it is apparent that other elements of the machine, more or less responsive to centrifugal force, might provide the surface that controls the bleeder outlet, and that the changes in such surface might arise from other causes.

Although but one specific embodiment of this invention has been herein shown and described, it will be understood that numerous details of the structure shown may be altered or omitted without departing from the spirit of the invention as defined by the following claims.

I claim:

1. A governor, comprising a wheel having a smooth periphery, fluid-driven means for rotating said wheel at speeds that subject the wheel to centrifugal expansion, and fluid-pressure supply means comprising a power supply passage for said fluid-driven means, a bleeder passage having its outlet opposed to the periphery of said

said wheel for control by the radial expansion and contraction of said wheel, a throttle valve controlling the fluid flow in said power supply passage, and means for adjusting said throttle valve through changes in the relative pressures in said fluid-supply and bleeder passages.

2. A governor, comprising a wheel having a smooth periphery, fluid-driven means for rotating said wheel at speeds that subject the wheel to centrifugal expansion, and fluid-pressure supply means comprising a power supply passage for said fluid-driven means, a bleeder passage having its outlet opposed to the periphery of said wheel for control by the radial expansion and contraction of said wheel, a needle throttle valve controlling the fluid flow in said power supply passage, and means for adjusting said throttle valve through changes in the relative pressures in said fluid-supply and bleeder passages.

10 3. A governor, comprising a wheel having a smooth periphery, fluid-driven means for rotating said wheel at speeds that subject the wheel to centrifugal expansion, and fluid-pressure supply means comprising a fluid supply passage for said fluid-driven means, a bleeder passage having its outlet opposed to the periphery of said wheel for control by the radial expansion and contraction of said wheel, a throttle valve controlling the fluid flow in said power supply passage,

15 30 comprising a balanced member actuated by changes in the relative pressures in said fluid-supply and bleeder passages.

4. A governor, comprising a wheel having a

35 smooth periphery, fluid-driven means for rotating said wheel at speeds that subject the wheel to centrifugal expansion, and fluid-pressure supply means comprising a power supply passage for said fluid-driven means, a bleeder passage having its outlet opposed to the periphery of said wheel for control by the radial expansion and contraction of said wheel, a throttle valve controlling the fluid flow in said power supply passage,

40 45 comprising a balanced member actuated by changes in the relative pressures in said fluid-supply and bleeder passages, and micrometrical adjustment means for setting said bleeder pipe outlet toward and away from said wheel.

5. The combination with a turbine rotor having a smooth periphery, and a nozzle for directing driving fluid to said rotor, of a governor comprising a throttle valve controlling said nozzle, a driving fluid supply chamber for said nozzle, an actuator for said throttle valve movable in said chamber and normally urged to open said valve by fluid pressure in said chamber, means for by-passing fluid behind said actuator, and a bleeder duct for such by-passed fluid having its outlet opposed to the periphery of said rotor,

55 60 whereby the escape of fluid from said bleeder duct is controlled by the expansion and contraction of said turbine rotor.

6. The combination with a turbine rotor having a smooth periphery, and a nozzle for directing driving fluid to said rotor, of a governor comprising a throttle valve controlling said nozzle, a driving fluid supply chamber for said nozzle, an actuator for said throttle valve movable in said chamber and normally urged to open said valve by fluid pressure in said chamber, means for by-passing fluid behind said actuator, a bleeder duct for such by-passed fluid having its outlet opposed to the periphery of said rotor, whereby the escape of fluid from said bleeder duct is controlled by the expansion and contrac-

tion of said turbine rotor, and means for adjusting said bleeder outlet with respect to said rotor.

RUDOLPH F. ONSRUD.
